UNITED STATES PATENT OFFICE

WILLIAM E. WHITE, OF ATLANTA, GEORGIA, ASSIGNOR TO SOUTHERN WOOD PRESERVING COMPANY, OF ATLANTA, GEORGIA, A CORPORATION OF GEORGIA

HIGHWAY GUARD FENCE

Application filed March 26, 1931. Serial No. 525,522.

This invention relates to highway guards or safety fences and, among other objects, aims to provide an improved, permanent wood guard having sheet metal applied to the inner face of a guard rail to present a smooth surface against which the hubs of automobiles or other vehicles may slide and adapted to be painted a bright color to guide or warn motorists. The idea is to provide a relatively cheap and very durable safety fence of this type in which all of the timbers are treated with creosote or an equivalent preservative so as to make the wood last as long, if not longer, than ordinary steel guards.

Other aims and advantages of the invention will appear in the specification, when considered in connection with the accompanying drawings, wherein:—

Fig. 1 is a top plan view of a portion of a safety fence or guard embodying the invention;

Fig. 2 is a fragmentary side elevation showing one section of the guard; and

Fig. 3 is a transverse sectional view showing the hub of an automobile wheel contacting with the inside of a guard rail.

Experience has demonstrated that ordinary road guards or fences made of untreated wood are unsafe because they soon rot. Moreover, the cost of upkeep, including paint and repairs is relatively high. Creosoted lumber or timber has not been used extensively to make permanent guards because the creosote makes the wood dark and the guard rails are not readily visible at night. Further, wooden guard rails, whether or not they are treated, offer considerable resistance to sliding movement of automobile hubs or wheels when the wheels strike them at an angle. In many instances, the hubs or wheel rims dig into the wood causing the car to stop more or less suddenly and turn over. Also, the force of the impact is sometimes sufficiently great to wreck the fence. For these reasons, expensive structural steel and expanded metal guards have been used extensively. But all steel guards soon rust and have to be painted, making the initial and upkeep costs almost prohibi-

tive. Ordinarily, they are not any more permanent than properly, creosoted timber. This invention therefore aims to overcome the foregoing objections to wood guards and to make them safer than the steel guards. 55

Referring particularly to the drawings, the safety fence, there shown, is made of a relatively dense wood, such as southern pine, treated with creosote. To obtain the best results, such wood or timber is treated with about 16 pounds of creosote to the cubic foot, which is applied under high pressure so as to penetrate the pores of the wood throughout. All of the timbers are preferably first cut to the desired shape or size 65 before they are treated.

The safety fence is here shown as comprising a series of posts 10 well anchored in the ground at the edge of a roadway or outside of the shoulder of a pavement. These 70 posts are ordinarily arranged from 8 to 10 feet apart around curves so as to afford adequate support for a longitudinal guard rail 11, also made of relatively heavy creosoted timber. The guard rail 11 is composed of 75 longitudinal sections secured on the insides of the posts at the same height as the hubs of ordinary automobiles. The width of the rail is preferably about 8 inches and the thickness about 4 inches. The end sections 80 of the fence and some of the intermediate sections are braced by means of ordinary diagonal braces 12 between the posts.

In accordance with this invention, sheet metal plates 13 are secured to the inner face 85 of the guard rail 11 to afford a smooth surface on which the hubs of automobiles may easily slide. 16 gauge, sheet steel strips of the same width as the guard rail are suitable for this purpose. The strips are shown as 90 being slightly longer than the sections of the guard rail 11 and they are secured to the rail as the fence is being assembled. Referring to Fig. 1, it will be noted that the plates are overlapped at the joints of the 95 guard rail in the direction of the traffic, which is indicated by an arrow. The end of each plate overlaps the joint and they overlap each other, thereby strengthening the joint. This avoids any obstruction to 100

a hub or wheel which strikes and slides along the guard rail. The plates are conveniently secured intermediate their ends to the sections of the guard rail 11 by means of flat-headed, galvanized bolts 14. Furthermore, their overlapped ends and the abutting ends of the guard rail sections are secured to the posts 10 by means of long galvanized bolts 15, thus avoiding the necessity of securing the plates separately to the guard rail.

The provision of the sheet metal plates on the inner face of the guard rail is not only advantageous from the standpoint of providing a sliding surface for the hubs of automobiles, but also provides a surface which is shown as being painted a bright color so that it is easily visible by motorists and denotes the direction of any curve. The plates are preferably first coated with red lead and then painted white, although they may be painted with so-called aluminum paint. However, the red lead prevents rust and the white paint will stick to it.

From the foregoing description, it will be seen that the thin sheet metal plates provide a hard sliding surface for the hubs of automobiles to strike and prevents the wheels from scouring into the timber. Moreover, the timber is sufficiently yieldable to absorb any hard shocks and thereby prevents serious damage which might occur if the entire fence were composed of structural steel. The creosote on the surface of the side rails will prevent rust of the inner surface of the guide plates. Furthermore, such safety fences can be built at a fraction of the cost of all steel guards and the combination of the treated timbers with the sheet metal plates makes the safety fence more durable. Due to the resiliency of the wood and the fact that the guard rail supports the sheet metal, preventing it from sagging, the improved guard is much safer than all-metal guards. The arrangement of the guard rail also prevents automobile wheels from striking the posts.

Obviously, the present invention is not restricted to the particular embodiment thereof herein shown and described.

What I claim is:—

1. In combination with a safety fence for highways having a plurality of wooden posts at the edge of the highway and a wooden guard rail on the insides of the posts, sheet metal strips secured to the inner face of the guard rail and overlapped in the direction of the traffic at the joints between the guard rail sections and the posts; and means securing both the guard rail and the overlapped portions of the strips to the posts.

2. In combination with a highway safety fence having a wooden guard rail secured to posts at such height as to deflect the

wheels of motor vehicles, a brightened sheet metal facing on the inside of the rail to provide a relatively smooth and readily visible sliding surface to deflect the hubs of vehicles and being sufficiently yieldable to permit the wooden rail to act as a cushion and absorb a portion of the shock; means securing the sheet metal at intervals to the rail and with respect to the posts so that the sheet metal also serves to reinforce the rail.

In testimony, that I claim the foregoing as my own, I have hereto affixed my signature.

WILLIAM E. WHITE.
